CLAIM

We claim the ornamental design for a water treatment assembly, as shown and described.

DESCRIPTION

FIG. 1 is a front perspective view of a water treatment assembly in accordance with an exemplary embodiment with access doors in a closed position.

FIG. 2 is a side view of the water treatment assembly shown in FIG. 1.

FIG. 3 is a top view of the water treatment assembly shown in FIG. 1.

FIG. 4 is a front view of the water treatment assembly shown in FIG. 1.

FIG. 5 is a front perspective view of the water treatment assembly shown in FIG. 1, with the access doors in an open position.

FIG. 6 is a front perspective view of the water treatment assembly shown in FIG. 5, with a water treatment component of the water treatment assembly in an extended position.

FIG. 7 is a top view of the water treatment assembly shown in FIG. 6; and,

FIG. 8 is a front view of the water treatment assembly shown in FIG. 6.
